6450X

S. Lane.

Threshing Mach.

Patented Apr. 6, 1831.

Appl'd. 1831. 75.

Samuel Lane
Holder Patent

6450X

The Schedule referred to in these Letters Patent and making part of the same containing, a description in the words of the said Samuel Lane himself of his improvements in the machinery for threshing and cleaning wheat and other grain.

To all whom it may concern. Be it known that Samuel Lane have invented certain improvements on the machine for threshing and cleaning wheat and other grain which I denominate The portable horse power threshing and cleaning machine and that the following is a full and exact description of the said machine with my improvements thereon. The power which I employ to drive my threshing machine is the endless chain and rail way horse power patented by me on the 17th of May 1830. The mode of doing this and likewise the general structure of the machinery is represented in the accompanying drawings. A represents the inclined plane upon which the horse walks. B. a cog wheel on the end of the larger drum over which the endless chain passes. This wheel may be 21 inches in diameter and the pinion C. which it drives six inches in diameter. The wheel D. may also be twenty one inches in diameter and the pinion E. on the shaft of the beater six inches. these relative proportions affording a sufficient velocity to the beater. The beaters have teeth which may be made either of wrought or cast iron they are to have on their faces the wedge like pointed form, seen at F. The hollow segment G. is best made of cast iron. It is furnished with teeth of the same form and length with those on the beater. The manner in which the teeth on the top those on the segment is shown at H. where they are drawn to a suitable size, and with the requisite space between them, to allow the straw and grain to pass. The teeth I usually make up most of two inches in length as, when shorter than this the same quantity cannot be threshed there not being sufficient space the

The pointed or wedge-like form of the teeth, their greater length than in other threshing machines and the span allowed between them for the straw are essential features of my machine, and distinguish it from others which have been made to thresh by means of teeth. The inclined board P. is for the purpose of feeding. The straw and grain after the threshing is complete are received upon an inclipt upon S. passing over rollers. On this they are carried up to the inclipt sieve and rake R. This sieve and rake are thus made slats of wood the length of the rollers are attached to leather straps or bands passing round the ends of the rollers. These slats ... may be two or three inches apart and they have cones projecting from their edges, forming a sieve. From the faces of the slats spikes project which form the rake to lay hold of the straw. The grain and chaff fall through upon a screen T. To this screen a vibratory motion is given from a crank on the shaft of the fan wheel M. (as in any other convenient way). The inclipt sieve and the fan wheel are driven by bands and wheels from the main machine. N.N. is a covering extending over the whole machinery. It is manifest that this threshing machine may be driven by other means than my patented Horse-power, I however deem this the most convenient. What I claim as my improvement are the particular form and management of the teeth as described and represented, the receiving the grain and straw upon an inclipt upon and thus carrying it up on the inclipt sieve and rake, the particular construction of the sieve and rake, and the general arrangement of the machinery, by which these objects are effected.
